UNITED STATES PATENT OFFICE.

WALTER H. MAZE AND JOHN NELSON, OF PERU, ILLINOIS, ASSIGNORS TO AMERICAN NICKELOID & MANUFACTURING COMPANY, OF PERU, ILLINOIS, A CORPORATION OF ILLINOIS.

POLISHING-MACHINE.

No. 908,115.

Specification of Letters Patent.

Patented Dec. 29, 1908.

Application filed December 21, 1907. Serial No. 407,530.

To all whom it may concern:

Be it known that we, WALTER H. MAZE and JOHN NELSON, citizens of the United States, residing at Peru, in the county of Lasalle and State of Illinois, have invented a new and useful Improvement in Polishing-Machines, of which the following is a specification.

Our invention relates particularly to machines for polishing sheet metal; and our primary object is to provide a machine of simple construction which is well adapted to the purpose of polishing metal in sheet form and which will serve to completely polish 10 one surface of each sheet of metal during the passage thereof through the machine.

It may be preliminarily stated that the invention, according to its preferred embodiment, involves the use of a pair of buffing or polishing rolls spaced apart a suitable distance and revolving in opposite directions, the shafts of said polishing rolls being journaled in stationary bearings with which the main frame is provided; a sheet-supporting roll corresponding with each buffing roll, and a feed roll located adjacent to each sheet-supporting roll; an inner adjustable frame carrying the sheet-supporting rolls and feed rolls and providing for the 15 simultaneous adjustment thereof with relation to the buffing rolls; a pair of rock-members supported on the inner frame, one sheet-supporting roll and one feed roll being carried by each of said rock-members to admit of the intermittent raising and lowering of the same with relation to the buffing rolls; a pair of cams loosely mounted upon a rotary shaft and adapted to be intermittently connected to and rotated therewith through the medium of clutches splined on said shaft; a rotary clutch-actuating shaft equipped with arms for throwing said clutches into operative engagement with said cams at suitable intervals, and a pair of 20 automatically actuated shields connected with said rock-members, one of said shields serving to protect the entering portion of the sheet metal while it is being passed beneath the first buffing roll and into the grip of the first sheet-supporting roll and the feed roll co-acting therewith, and the other of said shields serving to protect the last portion of the sheet from the second polishing roll as the sheet leaves the machine, 25 thereby to prevent the sheet from being

violently thrown by either polishing roll at a time when it is not gripped by a sheet-supporting roll and companion feed roll.

The invention is illustrated in its preferred embodiment in the accompanying drawings, 30 in which:

Figure 1 represents a front elevational view of our improved polishing machine, a front cross-member of the main frame being shown in dotted lines; Fig. 2, a side elevational view of the same; Fig. 3, a broken section taken as indicated at line 3 of Fig. 1 and showing one of the guides between the main frame and the inner frame; Fig. 4, a longitudinal vertical sectional view taken as 35 indicated at line 4 of Fig. 1; Fig. 5, a longitudinal vertical sectional view taken as indicated at line 5 of Fig. 1; Fig. 6, a broken horizontal sectional view taken as indicated at line 6 of Fig. 1 and showing the relation 40 of the cam-shaft, cams, clutches and the rotary shaft equipped with arms serving to actuate said clutches; Fig. 7, a side elevational view, on a reduced scale, of the inner adjustable frame; and Fig. 8, a sectional 45 view taken as indicated at line 8 of Fig. 1 and showing the arms of said rock-members in relation to stops therefor which are carried by a central standard which affords bearings for the central portion of the cam shaft and 50 the shaft which carries the clutch-actuating arms.

In the construction shown, A represents a main frame which is adjustable longitudinally on a base or shoe, A¹; A², an inner frame which is vertically adjustable with relation to the main frame; A³, standards rising from the inner frame and equipped at their upper ends with rigidly, connected 55 forwardly extending bracket arms A⁴ and 60 with rigidly connected rearwardly extending bracket arms A⁵; B, B¹ a pair of polishing rolls journaled in bearings at the upper front and 65 upper rear portions of the main frame, respectively; C, C¹, a pair of rock-members formed 70 rigidly with shafts c, c¹, respectively, which are journaled in bearings at the upper portion of the adjustable inner frame A²; C², C³, a sheet-supporting drum and co-acting feed-roll, respectively, journaled in the rock-member 75 C and located adjacent to the polishing roll B; C⁴, C⁵, a sheet-supporting roll and co-acting feed-roll, respectively, journaled in the rock-member C¹ and located 80 adjacent to the polishing roll B¹; C⁶, a shield 85

for the front polishing roll whose arms are pivotally connected with the arms A⁴; C⁷, a shield for the rear polishing roll whose arms are pivotally connected with the bracket 5 arms A⁵; C⁸, C⁹, links connecting the rock-members C, C¹ with said shields, whereby said shields will be automatically actuated when the rock-members are turned in their 10 bearings; D, a cam shaft journaled in the inner adjustable frame A² and equipped with a pulley D¹ through which continuous rotary motion is imparted to the cam shaft; D², D³, a pair of cams mounted loosely on the shaft D at its central portion and engaging, respectively, the cam-arms of the rock-members C and C¹; D⁴, D⁵, a pair of clutch members splined on the shaft D and adapted to connect said cams intermittently with the shaft D to rotate therewith; D⁶, D⁷, a pair of clutch-shifting levers, or yokes, mounted on standards D⁸ carried by the bottom member of the inner frame A²; E, a clutch-shifting shaft journaled in bearings in the inner frame A² and equipped with clutch-shifting 15 arms E¹, E² adapted to engage the clutch-shifting levers D⁶, D⁷, respectively; F (Figs. 1 and 4), a gear secured on the shaft D inside of one of the uprights of the inner frame A²; F¹, a gear meshing with the gear F and journaled upon a stud f carried by said upright; F², F³, a pair of gears meshing with the gear F¹ and journaled, respectively, on the shafts c and c¹; F⁴, a gear meshing with the gear F² and fixed on the shaft of the feed-roll C³; F⁵, 20 a gear meshing with the gear F³ and fixed on the shaft of the feed-roll C⁵, the gear-train thus described serving to communicate motion from the shaft D to the feed-rolls C³, C⁵, whereby said feed rolls are rotated in the 25 same direction; F⁶ (Figs. 1 and 2), a pinion secured on the shaft D outside of the adjacent upright of the inner frame A² and meshing with a gear F⁷ journaled on a stud F⁸ projecting outwardly from the adjacent upright of the inner frame A²; F⁹, a gear formed 30 integrally with or secured to rotate with the gear F⁷; F¹⁰, a gear meshing with the gear F⁹ and serving to communicate motion to the gear F¹¹ fixed on the shaft E; F¹², a bracket 35 carrying the gear F¹⁰, said bracket having one arm journaled on the shaft E and another arm adjustably connected with the bracket F¹³ carried by the frame A², the train of gears last described providing for the communication 40 of motion from the shaft D to the shaft E; G, mechanism for adjusting the inner frame A² with relation to the outer frame A; H, a table or guide over which the sheets of metal are fed into the machine; H¹, a curved 45 or dished guide carried by the inner frame and located between the front and rear sheet-supporting rolls; and H², a table or guide over which the sheets pass in leaving the machine.

60 65 The frame A is adjustable longitudinally

on its base or shoe by means of screws a, this adjustment being useful in regulating the tension of the belting from the line shaft. The main frame preferably comprises side members a¹ connected at their front and rear portions by cross-members a² and connected at their bottoms by a cross-member a³. The cross-member a³ is of channel-form and serves to receive and support the mechanism G which serves to adjust the inner frame A². The main frame is provided at its front end with brackets a⁴ supporting bearings a⁵ in which is journaled a shaft a⁶ which is equipped at one end with a pulley a⁷. The main frame also supports bearings a⁸ for the shafts b of the polishing rolls, said shafts b being equipped with pulleys b¹ in alinement with the pulley a⁷, said pulleys receiving a belt b² so arranged as to impart motion in opposite directions to the polishing rolls. 70 The inner frame A² comprises a horizontal member a⁹ located just above the cross-member a³ of the main frame; end standards a¹⁰ rising from the end portions of the horizontal member a⁹ and forming therewith a U-shaped inner frame; the standards A³ supported on the uprights a¹⁰; and a central standard a¹¹ rising from the horizontal member a⁹ and affording bearings for the shafts D and E and affording, also, stops a¹², a¹³ for 75 the cam-arms of the rock-members C and C¹, respectively. As shown in Fig. 7, the standards or uprights a¹⁰ are provided with bearings a¹⁴, a¹⁵ for the shafts c and c¹, with bearings a¹⁶ for the shaft D, and with bearings a¹⁷ for the shaft E. One of said standards is also provided with a bearing a¹⁸ for the stud F⁸. The outer surfaces of the upright members a¹⁰ of the inner frame A² are provided with vertically disposed, centrally located 80 flanges a¹⁹ which, as shown in Fig. 3, are located between guide-blocks a²⁰ with which the inner surfaces of the side frame-members a¹ of the main frame are equipped at points adjacent to the upper and lower ends of the inner frame A². As appears from Figs. 4 and 7, the side members, or uprights, a¹⁰ of the inner frame A² are equipped on their outer surfaces at their upper ends with flanges or short brackets a²¹ to which the 85 flanged lower ends of the standards A³ are bolted.

The polishing rolls B, B¹ may be of any suitable construction. As indicated by the arrows in Figs. 2 and 4, the front polishing roll rotates downwardly and to the front, while the rear polishing roll rotates downwardly and to the rear. The purpose of the arrangement is to produce the best possible result on the polished surface of the sheet 90 metal.

The rock-member C comprises the shaft c whose ends are journaled in the uprights a¹⁰ of the inner frame-member A²; members c² rigidly secured on said rock-shaft inside of 95

the upright members a^{10} of the frame A^2 and equipped with bearings c^3 for the end portions of the shaft of the feed-roll C^3 and with adjustable bearings c^4 for the ends of the 5 shaft of the sheet-supporting roll or drum C^2 ; a cam arm c^5 having a roller c^6 adapted to engage the cam D^2 ; and an arm c^7 depending from and rigid with the shaft c . The rock-member C^1 is similarly constructed, but 10 turned in the reverse direction and the parts are similarly lettered. The lower ends of the arms c^7 are provided with perforations which receive a rod c^8 upon which is a coil-spring c^9 which is confined between the end 15 of one of said arms and nuts c^{10} which are threaded on said rod and one of which bears against the other of said arms. Thus, the spring c^9 serves to yieldingly hold said arms c^7 separated and tends to maintain the rock-members C, C^1 in such position that the sheet-supporting rolls C^2, C^4 are elevated so as to support the sheet metal in contact with the polishing rolls. The adjustable bearings c^4 are movable toward and away from the 20 adjacent feed rolls, thus enabling the sheet-supporting rolls to be adjusted with relation to the feed rolls to accommodate different thicknesses of metal. The shield C^6 comprises a curved sheet-metal member, or 25 sector, c^{11} adapted to encircle a portion of the circumference of the polishing roll B , and arms c^{12} connecting the ends of the member c^{11} with pivots c^{13} carried by the front ends of the bracket arms A^4 . The construction 30 of the shield C^7 is the same, and the parts are similarly lettered. The link C^8 comprises two adjustably connected parts c^{14}, c^{15} , the upper end of the link being connected by a pivot c^{16} with the adjacent arm c^2 near the 35 pivot c^{13} of said arm, and the lower end of said link being connected by a pivot c^{17} with the shaft of the drum C^2 . It will be understood that there are a pair of these links C^8 , that is, one link at each end of the shield. 40 The arrangement at the rear shield is the same, and the parts are similarly lettered. 45 As has been indicated, the shaft D is journaled in the bearings a^{18} with which the end members of the inner frame A^2 are provided.

Motion is imparted to said shaft through the pulley D^1 by means of a belt d . The cams D^2, D^3 are located on opposite sides of the central standard a^{11} , and the non-adjacent sides of said cams are equipped with clutch-members having slanting teeth. The clutch-members D^4, D^5 are equipped with correspondingly slanting teeth adapted to engage said first-mentioned teeth. The clutch-shifting levers, or yokes, D^6, D^7 are connected with the standards D^8 by vertical pivots d^1 . As shown in Fig. 6, coil-springs d^2 are confined between the cams D^2, D^3 and the clutch-members D^4, D^5 , these springs serving to throw the clutch-members out of engagement with the cams. The free end of

each clutch-shifting lever is equipped with a lateral cam projection d^3 adapted to be engaged by a cam d^4 on the corresponding one of the arms E^1, E^2 . The clutch-shifting arms E^1, E^2 are angularly adjustable on the 70 shaft E , as indicated, thus providing for timing of the operations.

The bracket F^{12} which carries the gear-wheel F^{10} is connected by means of a bolt f with a slot f^1 which is struck in the bracket F^{13} on a radius from the shaft E , thus enabling the bracket F^{12} to be swung on the shaft E as a pivot in adjusting the bracket. This enables gears of a different size to be substituted for varying the speed ratio and timing 80 the operation of the shaft E , according to the length of the sheets of metal which are to be polished.

The mechanism G for adjusting the inner frame A^2 vertically comprises screws g having stems supported in bearings g^1 with which the cross-member a^3 of the main frame is provided; nuts g^2 received by sockets g^3 with which the cross-member a^3 of the inner frame A^2 is provided; sprocket wheels g^4 secured to the stems of the screws g ; and a sprocket chain g^5 connecting said sprocket wheels. Thus, when the sprocket chain g^5 is moved the screws will be simultaneously turned to raise or lower the inner frame, according to the direction of the movement of the screws. It will be noted that in an adjustment of the inner frame the sheet-supporting rolls, the feed-rolls co-acting therewith, the driving mechanism for the feed-rolls, and the means for automatically raising and lowering the shields, will be simultaneously adjusted. 95

The operation will be readily understood from the foregoing detailed description. 105 The shafts D and E and the feed-rolls C^3 and C^5 rotate continuously, as do also the polishing rolls B and B^1 . The cams D^2 and D^3 are normally loose on the shaft D ; and periodically each cam is connected to rotate with 110 the shaft D , owing to the shifting of the corresponding clutch lever by the appropriate arm on the shaft E . When a clutch-member is thrown into operative engagement, it is maintained in operative engagement, owing to the friction upon the teeth, until the high portion of the cam passes beneath the cam-arm which it actuates and rocks the corresponding rock-member, thereby depressing the sheet-supporting roll and feed-roll carried thereby. After the high portion 115 of the cam passes beneath the cam-arm, the tendency is for the cam-arm to rotate the cam in advance of the rotation of the shaft D , thereby relieving the friction upon the teeth of the clutch-members, thus permitting the spring to throw the clutch-member out of the operative position. The rock-member is then returned to its normal position under the action of the spring c^9 , the cam- 120

125 teeth of the clutch-members, thus permitting the spring to throw the clutch-member out of the operative position. The rock-member is then returned to its normal position under the action of the spring c^9 , the cam- 130

arm resting against the appropriate one of the stops a^{12} , a^{13} , and the cam passing to its starting position with the high portion down, in which position the cam is ready for 5 its turn in the next cycle of operations. A sheet is fed into the machine from the table, or guide, H when the shield C^6 is in its lowermost position, as indicated in Fig. 5, in which position the shield protects the sheet 10 metal from contact with the rapidly rotating polishing cylinder until the advance edge of the sheet metal is engaged between the feed roll C^3 and the co-acting sheet-supporting roll C^2 . The cam D^2 then passes from beneath the cam arm c^5 of the rock-member C, 15 permitting the spring c^9 to restore the feed-roll C^3 and the sheet-supporting roll C^2 to their elevated positions and at the same time raise the shield C^6 out of the way, thereby 20 bringing the metal sheet into contact with the polishing roll. The sheet is then fed automatically through the machine, and as the advance portion of the sheet passes beneath the polishing roll B¹, the advance margin 25 of the sheet, left unpolished by the roller B, is polished by the roll B¹. Before the metal sheet passes from the grip of the feed-roll C^5 and the drum C⁴, the cam D² acts to rock the member C¹ and depress the feed- 30 roll C^5 and drum C⁴, thereby carrying the metal sheet out of contact with the polishing roll B¹, the shield C⁷ at the same time being interposed between the final margin of the metal sheet and the polishing roll, so as to 35 obviate any danger of the sheet being struck by the polishing roll and thrown violently.

In our improved machine, the feature of a polishing roll in combination with a pair of co-acting feed rolls (or feed-roll and drum), 40 the polishing roll and pair of feed-rolls being automatically shiftable with relation to each other, is regarded as of primary importance; and, also, the feature of an automatically shifted shield for protecting the metal sheet 45 from the polishing cylinder is regarded as of great importance. The organization of parts shown and described is such as to provide a compact arrangement and a construction admirably adapted to its purpose. The 50 foregoing detailed description, however, has been given for clearness of understanding only, and no undue limitation is to be understood therefrom.

What we regard as new, and desire to secure by Letters Patent, is:

1. In a polishing machine of the character set forth, the combination with the polishing cylinder, feed-rollers located adjacent thereto and driving power, of means actuated by 60 the driving power for intermittently changing the adjustment of the rollers and cylinder, one with relation to the other, for the purpose set forth.

2. In a polishing machine of the character set forth, the combination with the polishing

cylinder, feed-rollers located adjacent thereto and driving power, of a shield for the polishing cylinder, movable into and out of operative position, and means actuated by said driving power for intermittently moving said shield and changing the adjustment of the rollers and cylinder, one with relation to the other, for the purpose set forth. 70

3. In a sheet metal polishing machine, the combination with the driving power, polishing cylinder, sheet-supporting roller located adjacent to said cylinder and feeding-roller located adjacent to said sheet-supporting roller, said sheet-supporting roller and feeding-roller coöperating to feed a sheet of 80 metal, of means operatively connected with said driving power and intermittently actuated thereby to move both the sheet-supporting roller and feeding-roller as a unit toward and away from the polishing cylinder. 85

4. In a machine of the character set forth, the combination of a polishing roll, a sheet-supporting roll located adjacent thereto, a feed-roll located adjacent to said sheet-supporting roll, said sheet-supporting roll and feed-roll operative to feed a sheet of metal, means for automatically moving the sheet-supporting roll and feed-roll as a unit toward and away from the polishing roll, a shield interposed between the sheet-supporting roll, 90 and the polishing roll, and means whereby the shield is automatically withdrawn when the sheet-supporting roll and feed-roll are moved toward the polishing roll. 95

5. In a sheet metal polishing machine, the combination with the driving power of a pair of coöperating polishing cylinders arranged one in advance of the other, a sheet-supporting roller and a feed-roller located adjacent to each of said polishing cylinders and coöperating to feed a sheet of metal, and means operatively connected with said driving power and intermittently actuated thereby for changing alternately the relative adjustment of said rollers at their adjacent polishing cylinders, for the purpose set forth. 100

6. In a machine of the character set forth, the combination of a polishing roll, a rock-member, sheet-supporting and feeding rolls journaled in said rock-member and located adjacent to the polishing roll, and means for intermittently actuating said rock-member. 115

7. In a sheet metal polishing machine, the combination with the driving power, of a pair of coöperating polishing cylinders arranged one in advance of the other, a pair of rollers, constituting a sheet-supporting roller and a feed-roller, located adjacent to each of said polishing cylinders operating between them to feed a sheet of metal and movable as a unit toward and away from the respective polishing cylinder, a shield located adjacent to each polishing cylinder and movable into and out of operative position, and means actuated by said driving power for 120 125 130

moving said shields and changing the relative adjustment between the rollers and cylinders at the respective polishing cylinders alternately, for the purpose set forth.

5 8. In a machine of the character set forth, the combination of a polishing cylinder, a movable member, a sheet-supporting roller and a feed-roller journaled in said movable member, a rotary cam-shaft, a cam loosely 10 mounted thereon and adapted to engage said movable member, and means serving to intermittently couple said cam to said rotary shaft, for the purpose set forth.

9. In a machine of the character set forth, 15 the combination of a pair of polishing rolls, a pair of rock-members located beneath and between the axes of said polishing rolls, sheet-supporting and feeding rolls journaled in said rock-members, a cam-shaft, and cams 20 on said shaft adapted to actuate said rock-members.

10. In a sheet metal polishing machine, the combination with the driving power, of a frame, a pair of coöperating polishing cylinders arranged one in advance of the other, 25 a pair of members movably supported on said frame, and located beneath and between the axes of said polishing rollers, a sheet-supporting roller and a feeding-roller 30 journaled on each of said movable members, a cam-shaft, cams on said shaft, and means operatively connected with said driving power for actuating said movable members.

11. In a machine of the character set forth, the combination with a pair of polishing cylinders, of a pair of rock-members located beneath and between the axes of said polishing cylinders, a sheet-supporting roller and a feeding-roller journaled in each rock-member, a cam-shaft, cams loosely mounted 40 thereon and adapted to engage said rock-members, clutch-members adapted to couple said cams to rotate with the cam-shaft, and a rotary shaft equipped with means for intermittently actuating said clutch-members.

12. In a sheet metal polishing machine, the combination with the driving power, of a pair of coöperating polishing cylinders, a pair of pivotally supported shields located 50 adjacent to the polishing cylinders and movable into and out of operative position, a pair of rock-members actuated by the driving power and operatively connected with said shields to move the same, a sheet-supporting roller and a feed-roller journaled in each of 55 said rock-members, all constructed and arranged to operate substantially as set forth.

13. In a machine of the character set forth, the combination with a pair of polishing cylinders, of a pair of rock-members, a sheet-supporting roller and a feeding-roller journaled in each rock-member, means 60 yieldingly holding the rock-members in position to maintain the metal sheet in contact with the polishing cylinder, and cams

serving to operate said rock-members, thereby to remove the sheet metal from contact with the polishing cylinders.

14. In a machine of the character set forth, the combination with a pair of polishing cylinders arranged one in advance of the other, and driving power therefor, a pair of movable rock-members located beneath said polishing cylinders, a sheet-supporting roller journaled in each of said rock-members and located beneath a polishing cylinder, a small feed-roller journaled in each movable rock-member above and between the axes of the sheet-supporting rollers, and means operative with said driving power for automatically moving said rock-members.

15. In a machine of the character set forth, the combination with a stationary frame, and driving power, of a pair of polishing cylinders journaled in said frame, an adjustable inner frame, movable rock-members supported on said inner frame, a sheet-supporting roller and a feeding-roller journaled on each of said rock-members, and means operatively connected with said driving power for actuating said rock-members, for the purpose set forth.

16. In a polishing machine of the character set forth, the combination of a main frame, a pair of polishing cylinders journaled thereon, and driving power therefor, of an adjustable inner frame, shiftable sheet-supporting rollers and feeding rollers movably mounted on said inner frame, a pair of shields, and means operative with said driving power for automatically and simultaneously shifting said rollers and shields.

17. In a polishing machine of the character set forth, the combination of a main frame, a pair of polishing cylinders journaled thereon, and driving power therefor, of an inner frame, vertical guides connecting the inner frame with the main frame, a pair of rollers comprising a sheet-supporting roller and a feeding-roller located adjacent to each of said polishing cylinders and movably mounted on the inner frame, and means mounted on the inner frame and operative with said driving power for automatically moving each of said pair of rollers, for the purpose set forth.

18. In a machine of the character set forth, the combination with a main frame and a pair of polishing cylinders journaled thereon, of an inner frame, a pair of rock-members mounted on the inner frame, a cam-shaft journaled on the inner frame, a sheet-supporting roller and a feed-roller mounted on each of said rock-members adjacent to each of said cylinders, gears connecting said cam-shaft with said feed rollers, a pair of clutch-members mounted on said shaft, an adjacent shaft journaled in said inner frame and equipped with clutch-shifting members, and gears connecting said cam-

shaft with said second-named shaft, for the purpose set forth.

19. In a machine of the character set forth, the combination of a main frame, a pair of polishing rolls journaled thereon, an inner frame, a pair of rock-members mounted on said inner frame, a pair of sheet-supporting and feeding rolls mounted on each of said rock-members, a spring connecting said rock-members and tending to throw the

sheet-supporting rolls into engagement with the polishing rolls, and cams for actuating said rock-members, thereby to depress the sheet-supporting rolls with relation to the polishing rolls.
